CLAIM

The ornamental design for sunglasses holder for a vehicle, as shown and described.

DESCRIPTION

FIG. 1 is a top, right side perspective view of the sunglasses holder for a vehicle showing my new design;

FIG. 2 is a similar perspective view thereof with the holder shown in the open position;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom plan view thereof;

FIG. 8 is a perspective view thereof, the sunglasses and visor being shown in broken lines for illustrative purposes only.

FIG. 1

FIG. 2

FIG. 3
